UNITED STATES PATENT OFFICE.

FREDERICK W. WALKER, OF MILWAUKEE, WISCONSIN.

ELECTRICAL BOND FOR RAILWAYS.

1,230,544.

Specification of Letters Patent. Patented June 19, 1917.

Application filed November 2, 1914. Serial No. 869,727.

To all whom it may concern:

Be it known that I, FREDERICK W. WALKER, a citizen of the United States, residing at Milwaukee, in the county of Milwaukee and State of Wisconsin, have invented certain new and useful Improvements in Electrical Bonds for Railways, of which the following is a specification, reference being had to the accompanying drawing, forming 10 a part thereof.

The main objects of this invention are to facilitate electrically bonding railway rails; to so construct the bonds and attach them to the rails as to prevent unauthorized or accidental removal or detachment thereof; to utilize the cheaper metals such as iron or steel, in the construction of the bonds; to directly connect adjoining rails independently of the splice bars in such a way as to permit of removing and replacing the splice bars without disturbing the bonds; and generally to improve the construction and increase the efficiency of bonds of this class.

It consists in the construction, arrangement and combination of parts as herein-after particularly described and pointed out in the claim.

In the accompanying drawing like characters designate the same parts in both figures.

Figure 1 is a side elevation of a rail joint and bond embodying the invention; and Fig. 2 is an enlarged cross section of the same on the line 2—2, Fig. 1.

Referring to the drawing, *a* designates portions of two railway rails, laid and connected in the usual manner end to end by splice bars *b*, which are clamped to opposite sides of the rail webs by bolts *c*, and form a slip or expansion joint between the rails, the bolt holes in the splice bars being elongated as indicated in Fig. 1, to allow for expansion and contraction of the rails.

The rails are electrically bonded or connected adjacent to their ends by a connector *d*, which may be constructed of any suitable metal, but preferably of some of the baser and cheaper metals, such as iron or steel, and is of any suitable shape and size in cross section, to afford the requisite current carrying capacity and to provide for its convenient attachment to the rail heads by metal fillers or binders *e*, which are fused by electricity, a gas torch, or other means, to the opposing faces of the rail heads and

connector, thereby forming strong, durable attachments of the requisite current carrying capacity.

The connector, which in the present instance is of quadrangular cross section and of uniform shape from end to end, is formed with straight aligned ends parallel with the rail heads and between its ends, with one or more expansion loops *f*, which extend obliquely downward and outward on the outer side of the rails over the outer splice bar *b*, the loop or loops being so shaped and disposed as to be out of alignment with the bolt holes in the splice bars and rails, and thus permit the insertion of the bolts into place in the splice bars and rails, and their withdrawal therefrom without disturbing the connector or its attachments to the rails. The expansion loop or loops, of which the connector shown has two, allow for the usual expansion and contraction of the rails and prevent undue strain on their attachments to the rails, or breaking the bond.

The straight aligned ends of the connector, which are formed with plain upper faces, are placed with such faces on opposite sides of the joint between the rails obliquely or at a vertical angle to the adjacent side of the rail heads, forming therewith V-shaped or upwardly flaring recesses which are open at the ends and unobstructed throughout their length, as shown in Figs. 1 and 2, the fillers or binders *e* being autogenously welded or fused to and uniting the opposing faces of the rail heads and connector.

The connectors as shown are easily and cheaply rolled or formed and are easily applied to the rails, the straight plain faced ends of the connectors being adjustable to any desired inclination or angle to the rails to form more or less flaring or open recesses for the reception of the fillers or binders and the most advantageous fusion thereof to the opposing faces of the rails and connectors by electric or blowpipe welding or autogenous soldering.

The fillers or binders may be made of any suitable metal, such as copper, steel or iron, or alloys of different metals, alloys of steel or iron and alloys of copper having been used with good results.

The bolts *b* and the splice bars can be readily removed and replaced without detaching or disturbing the connector, the outer splice bar when the bolts are removed,

being withdrawn or replaced either lengthwise or laterally through the space between the connector and rails.

Various modifications in the construction 5 and arrangement of parts may be made within the scope of the invention as defined in the following claim.

I claim:

10 In an electrical bond for railways the combination of rails laid end to end and connected by a splice bar bolted thereto, of a metal connector formed with an expansion loop and on opposite sides thereof with ends parallel with the rails and having faces 15 forming with the rail heads upwardly flar-

ing recesses, and metal binders inserted in said recesses and fused to and uniting the opposing faces of the rail heads and connector, the expansion loop extending obliquely to the rails downward and outward 20 over the splice bar and out of alignment with the bolt holes in the rails, and the splice bar being removable and replaceable without disturbing the connector or its attachments.

In witness whereof I hereto affix my signature in presence of two witnesses. 25

FREDERICK W. WALKER.
